(57) **CLAIM**

The ornamental design for a multiple part package for confectionary, as shown and described.

DESCRIPTION

FIG. 1 is a front view of the multiple part package for confectionary showing the inner and outer components in a separated state, showing my new design;

FIG. 2 is a front elevational view thereof, in a partially assembled state;

FIG. 3 is a front elevational view thereof in a fully assembled state, with the rear view being a mirror image thereof;

FIG. 4 is a front and side perspective view of the inner component of the package of FIG. 1 in an opened state; and, FIG. 5 is a front and side perspective view of the inner and outer components of FIG. 1 in a separated state.

1 Claim, 3 Drawing Sheets
